UNITED STATES PATENT OFFICE.

JERVIS R. HARBECK AND BEN K. FORD, OF DETROIT, MICHIGAN, ASSIGNORS, BY MESNE ASSIGNMENTS, TO DETROIT CAN COMPANY, OF DETROIT, MICHIGAN, A CORPORATION OF NEW JERSEY.

TUBE-FORMING MACHINE.

1,037,246.

Specification of Letters Patent.

Patented Sept. 3, 1912.

Application filed February 19, 1910. Serial No. 544,887.

To all whom it may concern:

Be it known that we, JERVIS R. HARBECK and BEN K. FORD, citizens of the United States of America, residing at Detroit, in 5 the county of Wayne and State of Michigan, have invented certain new and useful Improvements in Tube-Forming Machines, of which the following is a specification, reference being had therein to the accompanying 10 drawings.

The invention relates to tube forming machines of that type in which strips of paper or other flexible material are wound spirally upon a mandrel to form a tube. Such machines are adapted for the formation of cylindrical tubes, but where the mandrel is of any other form the spiral winding of the strips cannot be successfully performed. It is, however, possible after the formation of 15 a cylindrical tube, and while the material is still moist and in a plastic condition, to reform the structure into a non-circular section, and the present invention has for its object the incorporation of the reforming 20 mechanism as a part of the tube forming machine.

To this end, the invention consists, first, in the association of a reforming mandrel with the cylindrical mandrel upon which the 25 strips are first wound; further, in the construction by which the reforming mandrel is revoluble with the tube, the forming mandrel remaining stationary; and, further, in the peculiar construction, arrangement and 30 combination of parts, as hereinafter set forth.

In the drawings,—Figure 1 is a plan view of a tube-forming machine to which our improvements are applied; Fig. 2 is an enlarged longitudinal section through the reforming mandrel; Fig. 3 is a cross section on line α — α Fig. 2; and Fig. 4 is a perspective view, showing the manner in which the surface of the reforming mandrel is developed in changing from the circular to the non-circular section.

A is the frame, upon one end of which is mounted a bracket or support bearing B for the mandrel C which projects rearward 40 from its point of support.

D D' are strip-feeding guides through which the paper strips are fed after having first been coated with the glue or other adhesive material, at E E'.

55 F F' are pulleys upon opposite sides of

the mandrel, over which passes a belt G having a spiral wrapping about the mandrel and the tube in process of formation thereon. The construction is such that in operation the belt G will rotate and advance the 60 tube which is formed by the winding of the strips on the mandrel, said strips being arranged to overlap joints.

The construction thus far described is old and well known in the art, and forms no 65 part of the present invention, except in combination with the devices now to be described.

In alignment with the rear end of the mandrel C is a reforming mandrel H. This 70 is of the same size and cylindrical form as the mandrel C at the point of juncture therewith, but in passing rearward from this point the form is developed gradually into a non-circular section, and as illustrated this is of a substantially square section with slightly rounded corners. In developing this form, the perimeter is maintained of constant length, and consequently the tube is neither extended nor contracted, 75 but merely changed in shape.

In the formation of the tube, it has been found desirable to employ a stationary mandrel as the frictional resistance of the strip in passing around said mandrel aids in the 80 formation of a perfect spiral winding. When, however, the form of the tube is changed to a non-circular shape, it can no longer revolve, excepting by revolving the mandrel with it. We have therefore provided means for permitting the rotation of the mandrel H, which as shown comprises a shank I secured thereto and passing through the mandrel C in which it is supported upon ball bearings J. There is also 85 preferably provided a ball thrust bearing K at the forward end of the mandrel C and shank I. This construction permits the mandrel H to freely revolve with the work, while it is maintained in exact alignment 90 with the stationary mandrel C, and forms no impediment to the passage of the tube from the one to the other.

The reforming of the tube is accomplished while the latter is still "green" or in a 105 plastic condition by reason of the moisture which it contains. After reforming, to retain the shape it is necessary to dry the tube. This is preferably accomplished by an external heated former. As shown in 110

Fig. 3, this external former comprises a sleeve L, which is of the same shape as the developed portion of the mandrel H and is sufficiently larger to provide for the thickness of the tube. This sleeve is journaled in a bearing M preferably by ball bearings N, and the member M is chambered at O for steam or other heating agent. Thus, as the tube advances on the mandrel H, it passes into the sleeve L, which is maintained at a temperature sufficient to dry the tube, so that its shape will be retained.

To permit the alinement of the mandrel H and the sleeve L, the shank I is pivotally attached to the mandrel H, so as to provide a slight freedom for angular movement. Thus, the portion of the mandrel H which is within the sleeve L is free to adjust itself into axial alinement with said sleeve.

If desired, the rotating mandrel may be driven so as to relieve the tube from stress. It is necessary however to provide a yielding drive, so as to compensate for any leakage in the drive belts upon the tube. We have, therefore provided a drive connection comprising a sprocket P upon the end of the shank I at the forward end of the machine, which is connected by a chain Q with a sprocket R upon a shaft S, which shaft is positively driven in timed relation to the drive pulleys F F'. The sprocket R is not positively connected to the shaft S, but is driven thereby through the medium of a friction clutch T. The friction of this clutch is limited so that it will not drive the mandrel against the resistance of the tube if the latter is turning at a different speed, but will nevertheless relieve said tube of the stress of driving the mandrel alone. This drive connection is preferably speeded equal to or slightly in excess of the maximum speed of the rotation of the tube.

What we claim as our invention is,—

1. In a machine for forming tubes, the combination with means for spirally winding a flexible strip, of a stationary cylin-

drical mandrel upon which said strip is wound, a revoluble reforming mandrel forming an alined extension of said stationary mandrel and receiving the "green" tube therefrom, and means for drying said tube while in engagement with said reforming mandrel.

2. In a machine for forming tubes, the combination with means for spirally winding a paper strip, of a stationary mandrel upon which the strip is wound; a reforming mandrel constituting an alined extension of said stationary mandrel and over which the "green" tube is fed, and a revoluble heated sleeve surrounding said reforming mandrel through which the tube is fed.

3. In a machine for forming tubes, the combination with mechanism for spirally winding a flexible strip, of a stationary mandrel upon which said strip is wound, a revoluble reforming mandrel of different cross sections than and in alinement with the stationary mandrel, and means for driving said reforming mandrel permitting the rotation thereof at the speed of said winding means, and relieving the wound tube from stress.

4. In a machine for forming tubes, the combination with mechanism for spirally winding a flexible strip, of a stationary mandrel upon which said strip is wound, a revoluble reforming mandrel of different cross section than and in alinement with the stationary mandrel, and means for driving said reforming mandrel including a friction clutch permitting the rotation of the reforming mandrel at the speed of said winding means and relieving the wound tube from stress.

In testimony whereof we affix our signatures in presence of two witnesses.

JERVIS R. HARBECK.
BEN K. FORD.
